UNITED STATES PATENT OFFICE

JOSEPH L. O'BRIEN, OF EAST NORWALK, CONNECTICUT, ASSIGNOR TO THE CROFUT AND KNAPP CO., OF NEW YORK, N. Y., A CORPORATION OF CONNECTICUT

BLIND STITCH SEWING MACHINE

Application filed January 5, 1929. Serial No. 330,662.

The present invention relates to improvements in sewing machines, and has particular reference to the work guiding devices for blind stitch or other types of machines used for sewing tape over the reverse side of seams between two adjacent pieces of cloth.

When two pieces of goods are sewed together in the conventional manner, the outside of the resulting seam presents a smooth, even appearance, showing only a single line of attachment, whereas the reverse side shows also the two adjacent edges of the pieces joined. The edges of the cloth may or may not be ragged and uneven but in either case the reverse side presents an unsightly appearance, and accordingly manufacturers of quality articles conceal it by suitable linings, or by means of relatively narrow pieces of tape running lengthwise with the seam, and of sufficient width to completely cover and conceal the same. This is particularly true in the case of garments such as caps, or coats, in which the reverse sides of seams are frequently exposed to view.

One method of attaching such concealing tape is to lay it over the reverse side of the seam and then run a line of stitching adjacent each edge of the tape and along its entire length, the stitching extending through the tape and the cloth to which it is attached and being exposed on both sides. Such an operation may readily be accomplished on an ordinary type of sewing machine without difficulty but the resulting product is somewhat objectionable, for while the appearance of the reverse side has been improved, that of the outside has been materially depreciated owing to the exposed lines of stitching.

The most advantageous results are therefore obtained where the tape is blind stitched to the reverse side of the cloth so that the attaching lines of stitching will not be visible from the outside of the material.

There are numerous blind stitch sewing machines in use at the present time and in practically all such machines the material is made to travel at an angle to the needle path. That is, the material is not fed directly in alignment with the position of the presser foot

on the machine, but at an inclination to it, and it is therefore essential that effective means to mechanically guide the material be provided, since the operator cannot align it with the machine by eye.

Great difficulty has been heretofore experienced in the provision of guiding means which will accurately position the seamed material and tape in proper relative fixed relation during the blind stitching operation of a narrow tape to the reverse side of a seam. Due to the nature of the operation, the guiding must be extremely accurate and means must be provided to not only guide the material while the first line of stitching is being applied to the tape, but also while the second line is being applied.

It is a general object of the present invention to provide an attachment for a blind stitch sewing machine by means of which the blind stitching of tape on the reverse side of a seam may be readily effected.

Another object of the invention is the provision of a presser foot having a tape duct provided with two guide members attached thereto.

These and other objects of the invention will become more readily apparent upon a detailed study of the specification when read in connection with the accompanying drawings and will be pointed out in the appended claims.

Fig. 1 is a side elevation in part of a machine embodying the improvements of my invention.

Fig. 2 is a front elevation showing a fragmentary view of the presser foot and some of the adjoining parts shown in Fig. 1.

Fig. 3 is a top plan view of the presser foot shown in Fig. 2.

Fig. 4 is a bottom plan view of the presser foot.

Fig. 5 is a fragmentary plan view showing the position of the tape duct and guide members when the first line of stitching is applied to the tape.

Fig. 6 is a front elevation of the parts shown in Fig. 5.

Fig. 7 is a plan view showing the position of the tape duct and guide members when

the second line of stitching is applied to the tape.

Fig. 8 is a sectional view of a seam having a tape applied to its reverse side.

Fig. 9 is a fragmentary sectional view of the presser foot and plunger, immediately prior to the insertion of the needle.

Fig. 10 is a similar view showing the needle inserted.

In the drawings, 10 indicates generally the stitch forming mechanism above the presser foot and 11 designates the work handling mechanism below the presser foot. No attempt will be made to describe these mechanisms in detail as they form no part of the present invention and may be of any suitable conventional construction such as that disclosed in Letters Patent No. 1,172,812, granted to J. G. Lewis, on February 22, 1916.

The presser foot consists of a main body portion 12 recessed as at 13 and provided with lugs or ears 14 having holes for the reception of screws 15 by means of which attachment is made to the frame of the machine. Forwardly of the body portion 12 are toe portions 16 and 17, between which is situated the cloth recess 18 through which the material is adapted to be raised by the plunger 19 of the work handling mechanism so as to form a bend as shown in Fig. 10.

Attached to the toe portion 16 of the presser foot by means of the screw 20 is the needle deflector 21 and the usual guide 22 which is of light spring construction and of the type ordinarily employed on an ordinary presser foot.

The present invention contemplates the provision of novel tape positioning and guiding means, and the construction, function and operation of such means will now be described.

Fastened preferably by soldering to the bottom of the needle deflector 21 is a tape duct 23 having guide members 24 and 25 running longitudinally therewith at its forward portion and extending somewhat beyond the end of the tape duct. The two guide members are preferably formed of one piece, of which the central portion 26 is fastened in any suitable manner to the bottom of the tape duct, and the end portions are bent at right angles to form the guide members as shown in Fig. 6.

The tape duct is positioned adjacent to and in alignment with the edge guide 22 and extends preferably from the outer end of the needle deflector 21 to a point approximately midway to the cloth recess 18.

The edge guide 22 is positioned in alignment with the center of the cloth recess 18 in order that the edge to be guided will pass directly over the path of the plunger 19 of the work handling mechanism. This is essential as the plunger 19 and needle 27 co-operate with the looper (not shown) to form

the lines of stitching which should be along the edge of the material sewed.

As the material passes over the plunger 19 it is pushed upward into the cloth recess 18 of the presser foot by the action of the plunger, and the bend thus formed is penetrated by the needle 27 as shown in Figs. 9 and 10. The needle passes entirely through the upper portion of the cloth 28. It enters the tape 29 at only one point for each stitch, and emerges from the material 28 at a point outside the edge of the tape before being withdrawn along the arcuate path it follows. Exact guiding is essential since otherwise the needle might miss the tape entirely if it were not in perfect alignment.

Since the tape duct is positioned immediately adjacent the edge guide 22, one edge of the tape passing through the duct will necessarily pass over the center of the cloth recess 18 and always be opposite the point of the plunger 19.

The operation of the device is as follows:

The seamed material 28 is laid on the work plate or table 30 and made to pass between the presser foot and stitch forming mechanism, and the work handling mechanism.

The material is positioned by the operator so that the guide member 24 engages the seam as shown in Figures 5 and 6. Tape 29 is passed through the tape duct 23 and moved in the direction of the arrow, as the material 28 is moved in the same direction by the work handling mechanism 11, and the stitch forming mechanism begins the first line of stitching. The tape duct and guide members are stationary, since they are attached to the presser foot, and the material 28 is consequently held in true alignment by action of the guide member 24 in the seam, and the tape 29 is held in true alignment by the duct.

After the first line of stitching has been applied to the tape along the entire seam to be covered, the tape is cut from the reel, and the material is removed from the machine and turned so that the unsewn edge of the tape is in alignment with guide 25 as shown in Fig. 7. Guide 25 of the tape duct is in alignment with edge guide 22 so that as the material is again fed into the machine, the unsewn edge is directed over the center of the plunger path for stitching by the needle and looper as the tape passes under the tape duct.

Having thus described my invention, what I claim as new and desire to secure by Letters Patent of the United States is as follows:

1. In a blind stitch sewing machine, a presser foot having a cloth recess adapted to have a bend of cloth and tape projected therethrough, means for conducting the edge of a length of tape over the center of said

cloth recess, and guide members integral with said tape conducting means.

2. In a blind stitch sewing machine, a presser foot having a cloth recess adapted to have a bend of cloth and tape projected therethrough, a tape duct, and a guide member positioned on said tape duct.
- 10 3. In a blind stitch sewing machine, a presser foot having a cloth recess adapted to have a bend of cloth and tape projected therethrough, a tape duct having one edge thereof in alignment with the center of said cloth recess, and guide members positioned beneath the tape duct.
- 15 4. In a blind stitch sewing machine, a presser foot having a cloth recess adapted to have a bend of cloth and tape projected therethrough, a tape duct having one edge thereof in alignment with the center of said cloth recess, and guide members positioned beneath the tape duct, said tape duct being disposed at an angle to the axis of the presser foot, said guide members running longitudinally of the tape duct.
- 20 5. In a blind stitch sewing machine, a presser foot having a needle deflector and edge guide attached thereto, a tape duct secured to the bottom of said needle deflector, and guide members secured to the tape duct,
- 25 10 said tape duct being positioned to have one edge adjacent and parallel to the edge guide.

6. In a blind stitch sewing machine, a presser foot having a needle deflector and edge guide attached thereto, a tape duct adjacent and parallel to said edge guide attached to the needle deflector, a guide member attached to said tape duct, and a second guide member parallel to the first said guide member, the first said guide member being disposed under and parallel to an edge of the tape duct, the second guide member being disposed approximately under the center of said tape duct.

In testimony whereof, I have hereunto set
45 my signature.

JOSEPH L. O'BRIEN.
